UNITED STATES PATENT OFFICE.

JOSEPH HODGSON, OF PHILADELPHIA, PENNSYLVANIA, ASSIGNOR TO THOMAS DOLAN, OF SAME PLACE.

DESIGN FOR A SHAWL-FABRIC.

Specification forming part of Design No. 5,106, dated July 11, 1871.

To all whom it may concern:

Be it known that I, JOSEPH HODGSON, of Philadelphia, county of Philadelphia and State of Pennsylvania, have invented or produced a Design for a Shawl-Fabric, of which the following is a specification:

My shawl-fabric possesses two main characteristics: 1st, the pattern, no matter how it be varied in its details, invariably consists of stripes of reps-fabric following the direction of the warp, alternated with strips of a plaid pattern on ordinary shawl-fabric. 2d, the pattern is illuminated with stripes of silk, which are restricted to the plaid portion of the design.

In the accompanying drawing, Figure 1 illustrates a specimen of the shawl-fabric, and Fig. 2 another specimen.

In Fig. 1 the design consists of a series of stripes, A A, alternated with strips B B of a plaid pattern. Each stripe A consists of a collection of minor stripes, the number, size, and coloring of which may be varied at pleasure. It is a peculiar feature of my design that these stripes follow the direction of the warp-threads and are made in reps-fabric, while the strips B consist of shawl-fabric. The design of each strip B is formed by any combination of longitudinal and transverse stripes, forming a plaid pattern, in which are incorporated stripes of silk, the body of the fabric being composed of wool. Thus in Fig. 1 a a are the longitudinal stripes of silk, and b b the transverse stripes of the same ma-

terial. It will be observed that while these silken stripes impart brilliancy to the plaid portion of the design they are discontinued where the stripes A of reps-fabric occur, this restriction of the illuminating stripes being one of the features of my design. In the modification, Fig. 2, the same general characteristics are observed, the minor stripes of which the stripes A are composed in this pattern differing in form, color, and arrangement from those of the stripes A in Fig. 1. The plaid portion of the pattern in Fig. 2 also differs from that in Fig. 1, but it is illuminated by silken stripes x x and y y, arranged as shown. Other varieties of stripes A and illuminated plaid-patterns B may be substituted for those shown without departing from the general characteristics of my design.

I claim—

1. A design for a shawl-fabric, having stripes A A following the course of the warp, and alternated with strips B B of a plaid pattern, all substantially as set forth.

2. The plaid portion of the design, illuminated with stripes of silk on a woolen ground, as set forth.

In testimony whereof I have signed my name to this specification in the presence of two subscribing witnesses.

JOSEPH HODGSON.
